SCREEN

Walter J. Parks, Cleveland Heights, Ohio, assignor to The W. S. Tyler Company

Application April 25, 1941, Serial No. 390,309

5 Claims. (Cl. 209—395)

This invention relates, as indicated, to screens, but has reference more particularly to a deck or screen surface construction for screens.

In the prior art, a deck construction is disclosed in which a plurality of individually-removable parallel rods are supported in a flexed condition longitudinally of the screen body. This construction has several disadvantages, among which may be mentioned the following (1) the assembly and removal of the rods requires a considerable amount of time and labor (2) the rods, in being assembled and removed, are flexed beyond their point of ultimate setting, and (3) the arrangement of the rods longitudinally of the screen, that is to say, in the direction of movement of the screened material, creates a possibility of wedge-shaped particles lodging between the rods, thereby spreading the rods to the extent of permitting oversize material to pass.

It is a primary object of the present invention to provide a deck construction for screens, which not only overcomes all of the aforesaid disadvantages, but which has certain other inherent advantages resulting in improved screening efficiency.

Other objects and advantages of the invention will be apparent during the course of the following description.

In the accompanying drawings, forming a part of this specification, and in which like numerals are employed to designate like parts throughout the same,

Fig. 1 is a fragmentary plan view of one form of screen deck embodying the invention;

Fig. 2 is a transverse cross-sectional view, taken on the line 2—2 of Fig. 1;

Fig. 3 is a fragmentary cross-sectional view, taken on the line 3—3 of Fig. 1;

Fig. 4 is a view similar to Fig. 2, but showing an alternative form of deck construction;

Fig. 5 is a fragmentary cross-sectional view, taken on the line 5—5 of Fig. 4;

Fig. 6 is a fragmentary view showing the manner in which the clamping members of that form of the invention shown in Fig. 4 are mounted on the screen;

Fig. 7 is a view similar to Fig. 1, but showing a modified form of deck construction;

Fig. 8 is a cross-sectional view, taken on the line 8—8 of Fig. 7;

Fig. 9 is a fragmentary cross-sectional view, taken on the line 9—9 of Figs. 7 and 10;

Fig. 10 is a view similar to Fig. 8, but showing a still further modification of the invention, and

Fig. 11 is a fragmentary cross-sectional view, taken on the line 11—11 of Fig. 10.

Referring more particularly to that form of the invention shown in Figs. 1, 2 and 3, the screen comprises spaced side plates 1 and 2 between which the screen proper is disposed. The screen support comprises a panel or frame which is welded or otherwise secured to the side plates and consists of sides in the form of structural angles 3, having legs 4 providing ledges disposed in a common plane, and cross-members 5, also in the form of structural angles.

Welded or otherwise secured to the cross-members 5 of the frame, and extending longitudinally along the center of the screen in a T 6, the flange 7 of which is disposed in a plane considerably higher than that of the ledges 4. The flange 7 has secured to its upper surface, as by means of bolts 8, and nuts 9, a metal strip 10 to the upper surface of which is vulcanized a protective strip 11 of rubber or the like. Secured to the cross-members 5 at opposite sides of the stem of the T 6 are angles 12, which coact with the flange 7 of the T to form pockets or recesses for the reception of the rod spacing strips to be presently described.

Welded or otherwise secured to the cross-members 5 at points intermediate the T 6 and the angles 3 are metallic supports 13 to the upper edges of which are welded rails 14, the upper surfaces of which are disposed in a plane above that of the ledges 4 but somewhat below that of the flange 7 of the T 6.

Secured to the side plates 1 and 2 at points opposite the angles 3 are clamp retaining members 15 which have loosely secured thereto, as by means of bolts 16 and nuts 17, clamping members 18, which function in a manner to be presently described.

The screen proper comprises a series of rod sections or units, each of which consists of a plurality of parallel metallic rods 19, a pair of spaced blocks 20 of rubber or the like having spaced openings into which the ends of the rods 19 extend, and a block 21 of rubber or the like through which the central portion of each rod extends. The blocks 20 have metallic wear strips 22 vulcanized to their upper surfaces, while the blocks 21 have metallic wear strips 23 vulcanized to their lower surfaces.

In assembling the rod sections or units to form the screen, the clamping members 18, which, it will be noted, are in sections of substantially the same length as the rod units, are first loosened so as to permit their movement to a position such

that the rod units can be positioned as indicated by the dot and dash lines in Fig. 1, that is, with one end of each unit in the pocket formed by the angle 12 and flange 7 of the T 6, and the block 21, or rather the wear strip 23 thereof, resting on the rail 14. Thereafter, the clamping members 18 are moved to the position shown in Fig. 2 and locked in such position by tightening the nuts 17 and causing the upper edges of such members to engage retainer plates 24, secured to the side plates 1 and 2 by means of screw-bolts 25 and nuts 26. Movement of the clamping members 18 to the aforesaid position results in the rods 19 of the units being cambered to the condition shown in solid lines in Fig. 2. In this condition of the rod units, the inner ends of the units exert an upward pressure on the flange 7 of the T 6, the outer ends of the units exert an upward pressure on the clamping members 18 and the central portions of the units exert a downward pressure on the rails 14. This pressure is sufficient to retain the units in position under virtually all conditions of operation of the screen, it being understood that the screen body is to be electrically or mechanically vibrated in accordance with well-known practices in the screening art.

In order, however, to eliminate any possibility of the units being moved to any appreciable extent laterally during the operation of the screen, metallic retainer bars 27 are secured to the angles 3 to limit such movement of the units.

The resiliently mounted unitary structure of the rod elements, together with the transverse mounting of the rods produces important practical advantages, some of which may be enumerated as follows:

(a) The use of rubber spacing blocks for holding the rods permits the latter to be inserted into holes which may be as small as or smaller than the diameter of the rods without undue force being necessary.

The resiliency of the rubber permits the hole to expand for the insertion of the rod and clamps it firmly in place after the assembly is complete. This is quite important as it has been found in practice that any clearance between the rod and holding element allows the rod to vibrate and causes wear at the junction of the holding strip and the rod. If the holding strip is of metallic material a disturbing noise would also be present. The firm clamping of the rod in the rubber also prevents the material being screened from working into the joints, and if abrasive, as is usually the case, causing premature failure of the screen section.

(b) The rubber spacing strips are on some parts of the deck, protected from wear and also, under ordinary conditions, will outwear the metallic rods of the section so that it is necessary to be able to reclaim these pieces when the rods are worn, and insert new rods. This is particularly important when it is recognized that the rubber strips are considerably more costly than the rods. This can be readily done in the construction described.

(c) When the screen sections of any machine are replaced or repaired it is necessary to shut down the machine and take it out of production. Where the machine is operating continuously the time thus lost is important. If the deck of a machine has to be rebuilt rod by rod and the deck is composed of a large number of small diameter rods this lost time can be very expensive from a production standpoint.

(d) The rods, during assembly of the units, are not stressed beyond the point of their ultimate setting, and there is therefore no likelihood of imparting a permanent camber set to the rods.

(e) The arrangement of the rods transversely of the screen body, that is, in a direction transverse to the direction of movement of the screened material, avoids the possibility of wedge-shaped particles becoming lodged between the rods and causing the rods to spread to the extent of permitting oversize material to pass through the screen.

The rods are secured to the rubber blocks 20 and 21 by means of a press fit sufficient to prevent appreciable movement between the rods and blocks during handling of the units or during the screening operations. This permits the rods to be assembled and removed in units, rather than individually, although after a unit has been removed from the screen, one or more of the rods may be removed from the blocks for replacement purposes.

The aforesaid construction whereby the rods are assembled in units outside of the machine and inserted in units in the machine results in a very substantial reduction of time so lost and is important to the operators of the same.

In cases where the rods require considerable force to produce the camber, the alternative form of construction shown in Figs. 4, 5 and 6 is preferably employed. In this form of construction, the clamping members 30 are in the form of castings having ears 31 and 32 which project through openings 33 and 34 respectively in the side plates 1 and 2. The side plates have channels 35 secured thereto, as by bolts 36 and nuts 37, and the lower flanges 38 of these channels provide stops for the heads of bolts 39 which extend through the channel flanges as well as the ears 31 and 32 of the clamping members 30.

The clamping members 30 are retained in the unit clamping position by means of nuts 40 which are in threaded engagement with the bolts 39 and bear against the ears 31. Lock nuts 41 are provided to lock the nuts 40 against movement.

By loosening the nuts 40 and 41, the clamping members 30 can be moved upwardly to an extent limited only by the length of the slots or openings 33 and 34.

It will be further noted that the ears 32 of the clamping members are provided with shoulders 42 which function to restrain lateral movement of the rod units in a manner similar to the bars 27 in that form of construction shown in Fig. 1, and that the clamping members, in this case, have secured thereto wear-resistant facings 43, of rubber or the like.

Where considerable camber is required in the rods, the rod units will, prior to being cambered, have their outer edges at a considerable elevation above the ledges 4', and the clamping members, in order to continuously press the units from their elevated position to their final position, must have a long range of action. Such a range of action is permitted by the form of construction shown in Figs. 4, 5 and 6.

In that form of the invention shown in Figs. 7, 8 and 9, the rod deck units extend entirely across the screen, and are supported at two laterally spaced points instead of one. Each unit, in this case, consists of a plurality of parallel rods 50, the ends of which are secured in rubber sleeves 51, which, as shown in Fig. 9, are clamped between metallic bars 52 and 53, having cooperat-

ing recesses in which the sleeves are partially received. The bars 52 and 53 are clamped to each other by means of flat headed cap screws 54, and nuts 55 disposed in counterbored openings 56 in the bars 52.

The rods 50 are encased in rubber sleeves 57 at points intermediate the centers and ends thereof, and these sleeves are encased in metallic clamp bars 58 and 59, which are similar to the bars 52 and 53. These bars are clamped together as well as to angles 60 of the screen frame by means of bolts 61. It may be noted, at this point that the clamp bars 58 and 59 do not extend the entire length of the screen, but are only as long as the clamping members 18, thereby permitting the units to be separately removed from the screen when desired. It may be further noted that the rods are maintained in an arched condition in a manner similar to the rods of the units shown in Fig. 2.

In that form of the invention shown in Figs. 10 and 11, the rod deck units extend entirely across the screen, as in the previously described form of the invention, but the units are held down at their centers to create the double-arch effect shown in Fig. 10, which effect corresponds with that shown in Fig. 2. For this purpose, the centers of the rods 69 which are encased in rubber sleeves 70, are secured to an angle 71 of the screen frame by means of clamp bars 72 and 73, and bolts 74 which extend through these bars and into said angle.

The portions of the rods 69 intermediate the ends and centers are clamped to angles 75 of the screen frame in the manner clearly shown in Fig. 11. The rods, in this case, are disposed between semi-cylindrical rubber sleeves 76 disposed in openings therefor in a clamp bar 77, and a rubber strip 78 which is vulcanized to a metal strip 79, which is secured to the angle 75 by means of bolts 80 and nuts 81. The bars 77 are secured to the angles 75 by means of bolts 82 and nuts 83. The units, in this case, are removable from the screen in the same manner as the units of that form of the invention shown in Fig. 8.

It is thus seen that in all of the modified forms of the invention which have been described, the advantages which inhere in the first form of the invention are also present.

It is to be understood that the form of my invention, herewith shown and described, is to be taken as a preferred example of the same, and that various changes in the shape, size and arrangement of parts may be resorted to, without departing from the spirit of my invention, or the scope of the subjoined claims.

Having thus described my invention, I claim:

1. A rod deck unit for screens, said unit comprising a plurality of metallic rods, rubber sleeves encompassing the ends of said rods and points on said rods intermediate the ends thereof, metallic clamp bars engaging said rubber sleeves and serving to maintain said rods in spaced parallel relation, and means securing said bars to each other.

2. A rod screen comprising a screen frame including a pair of longitudinally extending spaced side members each having an inwardly extending rod-end supporting ledge thereon, one of said ledges overhanging its side member and provided with a downwardly facing rod-end supporting surface, the other of said ledges being provided with an upwardly facing rod-end supporting surface, a rod tensioning member carried by the

frame intermediate said side members and disposed generally parallel thereto, said tensioning member having a rod supporting portion disposed to support the rods intermediate their ends and from beneath, a unitary rod deck panel including a plurality of metallic rods and rubber mounting bars secured to said rods adjacent their ends for maintaining the rods in spaced parallel relation independently of said frame, the rods of said panel lying across said tensioning member with the mounting bar at one end of the panel disposed beneath said overhanging ledge and in engagement with said downwardly facing rod-end supporting surface thereof, and an adjustable clamping member on the side member having said other ledge, said clamping member being operable to clamp the mounting bar at the opposite end of the panel firmly against the upwardly facing rod-end supporting surface of said other ledge, said rod supporting portion of said tensioning member being disposed at an elevation with respect to said ledges as to thereby bow said rods under tension.

3. A rod screen comprising a screen frame including a pair of longitudinally extending spaced side members each having an inwardly extending rod-end supporting ledge thereon, one of said ledges overhanging its side member and provided with a downwardly facing rod-end supporting surface, the other of said ledges being provided with an upwardly facing rod-end supporting surface, a rod tensioning member carried by the frame intermediate said side members and disposed generally parallel thereto, said tensioning member having a rod supporting portion disposed to support the rods intermediate their ends and from beneath a unitary rod deck panel including a plurality of metallic rods and rubber mounting bars secured to said rods adjacent their ends and at the intermediate portions thereof adapted to engage said tensioning member for maintaining the rods in spaced parallel relation independently of said frame, the rods of said panel lying across said tensioning member with the intermediate mounting bar supported upon said tensioning member and with the mounting bar at one end of the panel disposed beneath said overhanging ledge and in engagement with said downwardly facing rod-end supporting surface thereof, and an adjustable clamping member on the side member having said other ledge, said clamping member being operable to clamp the mounting bar at the opposite end of the panel firmly against the upwardly facing rod-end supporting surface of said other ledge, said rod supporting portion of said tensioning member being disposed at an elevation with respect to said ledges as to thereby bow said rods under tension.

4. A rod screen comprising a screen frame including a pair of longitudinally extending spaced side members each having an inwardly extending rod-end supporting ledge thereon, one of said ledges overhanging its side member and provided with a downwardly facing rod-end supporting surface, the other of said ledges being provided with an upwardly facing rod-end supporting surface, a rod tensioning member carried by the frame intermediate said side members and disposed generally parallel thereto, said tensioning member having a rod supporting portion disposed to support the rods intermediate their ends and from beneath, the other of said ledges being disposed below the level of the rod engaging portion of the tensioning member, a unitary rod deck

panel including a plurality of metallic rods and rubber mounting bars secured to said rods adjacent their ends and at the intermediate portions thereof adapted to engage said tensioning member for maintaining the rods in spaced parallel relation independently of said frame, the rods of said frame, the rods of said panel lying across said tensioning member with the intermediate mounting bar supported upon said tensioning member and with the mounting bar at one end of the panel disposed beneath said overhanging ledge and in engagement with said downwardly facing rod-end supporting surface thereof, and an adjustable clamping member on the side member having said other ledge, said clamping member being operable to clamp the mounting bar at the opposite end of the panel firmly against the upwardly facing rod-end supporting surface of said other ledge to thereby bow said rods under tension, and stop members on the screen frame adjacent the rod ends for limiting longitudinal movement of said rods.

5. A rod screen comprising a screen frame including a pair of longitudinally extending spaced side members each having an inwardly extending rod-end supporting ledge thereon, one of said ledges overhanging its side member and provided with a downwardly facing rod-end supporting surface, the other of said ledges being provided with an upwardly facing rod-end supporting surface, a rod tensioning member carried by the frame intermediate said side

members and disposed generally parallel thereto, said tensioning member having a rod supporting portion disposed to support the rods intermediate their ends and from beneath, the other of 5 said ledges being disposed below the level of the rod engaging portion of the tensioning member, a unitary rod deck panel including a plurality of metallic rods and rubber mounting bars secured to said rods adjacent their ends and at the intermediate 10 portions thereof adapted to engage said tensioning member for maintaining the rods in spaced parallel relation independently of said frame, the rods of said panel lying across said tensioning member with the intermediate mounting bar supported upon said tensioning member and with the mounting bar at one end of the panel disposed beneath said overhanging ledge and in engagement with said downwardly facing rod-end supporting surface thereof, and 15 an adjustable clamping member on the side member having said other ledge, said clamping member being operable to clamp the mounting bar at the opposite end of the panel firmly against the upwardly facing rod-end supporting surface of said other ledge to thereby bow said rods under tension, and metal wear plates secured to said 20 mounting bars on the surfaces thereof which are opposed to the overhanging ledge, the tensioning member and the adjustable clamp respectively.

WALTER J. PARKS.
